UNITED STATES PATENT OFFICE.

ALBERT DU BRUL, OF FORT THOMAS, KENTUCKY, ASSIGNOR TO THE MILLER, DU BRUL AND PETERS MANUFACTURING CO., OF CINCINNATI, OHIO, A CORPORATION OF OHIO.

CIGARETTE-MACHINE.

1,237,760.

Specification of Letters Patent. Patented Aug. 21, 1917.

Application filed December 17, 1913. Serial No. 807,256.

To all whom it may concern:

Be it known that I, ALBERT DU BRUL, a citizen of the United States, residing at Fort Thomas, in the county of Campbell and

5 State of Kentucky, have invented certain new and useful Improvements in Cigarette-Machines, of which the following is a specification.

This invention relates to improvements in 10 cigarette machines, particularly in high speed machines of the continuous rod type.

In the operation of high speed cigarette machines of the continuous rod type, it is well known that there is a considerable irregularity in the distribution or showering of the tobacco that forms the filler, and that machines do not work with equal regularity on all occasions. This is due to a variety 15 of causes affecting the condition of the tobacco as it is given to the machine operator to be worked up. Some tobaccos are of heavy body, others are light. Some tobaccos are cut to a comparatively coarse fiber, others are cut comparatively fine. In some 20 tobaccos the fiber is long and in others short. Some tobaccos must be worked comparatively damp, others comparatively dry. Besides, there is considerable variation due to atmospheric or meteorological conditions.

25 All the above differences in condition of the tobacco make it necessary that the feeding apparatus of a high speed cigarette machine be itself susceptible of such adjustment, so that no matter what tobacco is used, and no 30 matter in what condition it may come to the machine, the resulting rope or filler will be uniform in density throughout, and not too dense in some places and too spongy in others. Unless the filler is uniform, much 35 waste results from throwing out the cigarettes that are either too dense or too loose and consequently a relatively great direct loss is incurred. Besides the direct loss of labor and material there is the indirect loss 40 of production caused by numerous stoppages to attempt to correct the difficulties.

Further it has been found to be more difficult to secure merchantable regularity when making cigarettes of a small cross section. 45 A given excess or deficiency in the quantity of tobacco fed is proportionately greater in

a small cross section than it is in the larger sizes and is therefore more noticeable and the proportion of rejections is consequently higher.

55

One of the objects of my invention is to produce a machine that is readily adjustable in various parts so as to be able to feed tobacco to the density desired, regardless of the condition of the tobacco, so that the machine can be worked with equal facility in making cigarettes of any size or shape, and with any tobacco in any condition that may be pleasing to the consumer.

60

A further object of my invention is to provide positive driving means for such an adjustable feeder, so as to eliminate the possibility of the machine varying its feeding once the proper adjustment is made.

65

In operating machines of this character, 70 it frequently happens that nails and other hard foreign bodies become mixed with the tobacco. If such bodies are of a size too large to pass between the usual forming devices, such devices are seriously damaged 75 with a consequent cost for stoppage and repair of the machine.

70

A further object of my invention is to provide forming means that will permit the 80 passage of such foreign substances therethrough without damage.

80

A further object of my invention is to improve the construction of conveying means usually employed in such machines for conveying the tobacco as from the feeding to 85 the forming and wrapping device.

85

In operating machines of the character mentioned, a common cause of stoppage, with a consequent loss of production arises, from the fact that the paper some times 90 breaks. It is well known that the paper must be under proper tension which varies with the character of the paper and the size of the reel. Machines of the character described are generally provided with a paper 95 reel brake, which when the machine is in operation retards the revolution of the reel so as to maintain tension on the paper, sufficient to prevent the reel from overrunning or unwinding faster than the paper is used. 100 When running, this tension some times changes, as when a lump of tobacco or some

other substance of abnormal size or density passes through the wrapping tube. In such cases, there is a slowing down of the paper in the tube, but the inertia of the reel causes the paper to slacken at the point of unwinding. Then when such large body passes out of the tube, the friction being relieved, the slack is taken up, but the reel having slowed down after overrunning, it is brought to speed again with a jerk when the slack is used up. If the paper is of a very thin quality, or if at any point that may be subject to such a jerk its strength should be impaired, the jerking so caused frequently breaks the paper.

Again, whenever the machine is stopped the paper is slackened by the overrunning of the reel. In starting up, the operator must be careful to back up his reel to the proper tension, but this is frequently forgotten and the consequence is that the paper breaks and more time is lost in stringing it through the wrapping tube before starting again. Even though the operator does back up his reel properly, it takes him an appreciable length of time to do so. This difficulty is inherent in the ordinary paper-reel brake as usually provided on machines of the character described, for if the brake is set tight enough to prevent the paper from overrunning, it creates an excessive drag on the paper when running, and its pressure is an added force to be overcome in starting. Another difficulty with the usual brake is its lack of means for quickly and properly adjusting the braking pressure exerted according to the character of the paper, or other conditions that make such adjustment desirable.

40 A further object of my invention is to provide a paper-reel brake capable of sensitive adjustment according to the conditions of the paper and diameter of the reel, and further to provide an automatic tension device for the paper that will prevent breakages of paper due to slack in the same.

With these and other objects, not specifically mentioned, in view, the invention consists in certain constructions, combinations, improvements and parts which will be hereinafter fully described and then specifically set forth in the claims hereunto appended.

55 In the accompanying drawings which form a part of this specification and in which like characters of reference designate the same or like parts,

Figure 1 is a side elevation of a continuous cigarette machine embodying my invention;

Fig. 2 is a top plan view of the same;

Fig. 3 is a detail side elevation of the automatic feeder of the machine;

Fig. 4 is a top plan view of the automatic feeder;

Fig. 5 is a detail side elevation of the automatic feeder opposite to that shown in Fig. 3;

Fig. 6 is an enlarged detail top plan view of the right hand portion of Fig. 1;

Fig. 7 is an enlarged detail view, and

Fig. 8 is a top view of the adjustable brake for the paper reel.

Fig. 9 is a section along line 9—9 Fig. 3 and

Fig. 10, a top plan view, partly in section, of the presser roll and its bearings.

The reference numeral 1 designates the frame of the machine, which may be of any suitable construction, on which a main drive shaft 3 is suitably mounted, the driving pulley 2 being secured to said shaft. A bevel pinion on the shaft 3 drives the bevel gear wheel 4, which in turn drives the shaft 5, to which are fastened the bevel gears 6 and 7. The driving gears 6^a and 7^a, are secured, respectively, to the vertical shafts 8 and 9. 10 and 11 are filler-forming disks secured to the vertical shafts 8 and 9 and are operated thereby.

12 is a pulley secured to the shaft 5, which drives a belt 13 over the pulley 14 running on a stud 5^a. Such a belt must necessarily be provided with tension means.

In ordinary practice, the tension on the belt 13, which is frequently of steel, is such as to tend to strain the shaft 5 and the stud 5^a toward each other, causing frequent cutting and renewal of such parts. In my construction, I provide means between the two pulleys 12 and 14, whereby tension may be put on the belt 13 without straining on said shaft or stud. Such means may vary within wide limits without departing from my invention.

The pulley 14 is journaled on a stud 5^a secured to a sliding block 14^a, which block is suitably mounted in the frame 1.

To illustrate one form of such tension means, on the frame 1, I show a slide housing 15 in which are slidably mounted the arms 16 and 17. The arms 16 and 17 are provided at each end, respectively, with abutment rollers 18 which contact with the pulleys 12 and 14, as clearly shown in Fig. 1. These arms 16 and 17 are adjustably secured together by means of the adjusting screw 19, by means of which the distance between the axis of the rollers 18 is regulated, the slidable mounting 14^a of the pulley 14 permitting of adjustment, whereby the tension of the belt 13 on pulleys 12 and 14 is regulated. By reason of the abutment rollers 18 and the sliding mounting of the pulley 14, said abutment rollers take and equalize the pulling strain at the rims of the pulleys and thus relieve the shafts of the pulleys 12 and 14 from this strain. I not only regulate the belt tension but by this means, the strain on the shaft and stud 130

which overhang from the frame is avoided, as well as the consequent liability of cutting such parts and their bearings.

The pressure wheel 55 is secured to a horizontal shaft 57 driven by helical pinion 54 which is driven by helical gear 53, secured to vertical shaft 8. This pressure wheel compresses the tobacco on belt 13 where the tobacco is gathered by the disks 10 and 11 to form the filler for the cigarettes. The pressure wheel runs very close to the belt 13 to compress the tobacco and some times nails and other hard substances having become mixed with the tobacco, pass under this wheel. Such substances are liable to break, bend or injure the driving connections of the wheel unless some provision is made to permit the wheel to rise.

To avoid damage to said wheel and other parts of the machine, I provide means for permitting the wheel to rise, thus allowing such substances to pass through. Such means may vary within wide limits without departing from my invention, and as an illustration of one form of the invention, I show the horizontal shaft of said pressure wheel 55 journaled in an eccentric 58, which is revoluble in a housing 59. This eccentric has a flattened top portion in the middle to which is fastened a bar lever 60 having a spring 61 with a set screw 61^a at one end and a set screw 62 at its other end. Said set screws 61^a and 62 regulate the height above the steel belt at which the pressure wheel 55 normally operates, see Figs. 6, 7 and 10.

If a nail or other hard foreign substance passes under the pressure wheel 55, the pressure revolves the eccentric 58 counter-clockwise, see Fig. 7; tilting down the left end of lever 60, which overcomes the pressure of spring 61 at one end of the lever 60, which revolving motion raises the pressure wheel, thereby eliminating all danger of damage to the driving mechanism.

The filler-forming disks 10 and 11, which may or may not have their edges grooved, work sufficiently close together at their peripheries to form the cigarette filler according to the size desired.

Therefore, if a nail or other hard substances should happen to pass between the disks, with the tobacco, the driving mechanism of the disks is liable to be damaged.

To prevent such damage, I provide means permitting the spreading of one or both of these disks when such substances pass between, and returning the disks to their normal position after the passage of such substance.

Such means may vary in construction within wide limits and may apply to one or both disks without departing from my invention. To illustrate one form of the invention, I show a single disk mounting

similar to that described in connection with the mounting of the pressure wheel.

In operation with such mountings, I have found that substances which would otherwise cause breakage pass both the pressure wheel and disks without causing damage.

In the illustration of the mounting for the disks, the housing is marked 63, the eccentric 64, the bar lever 65, the spring 66 and the set screw 62^a.

75

My improvement in machines of the class described, that relates to the provision of a sensitively adjustable brake for the paper reel, may be accomplished by means that may vary within wide limits without departing from my invention. I illustrate one form of such means showing a reel of paper 67, the reference numerals 68 and 69 indicating different positions of the web of paper, which will be hereinafter referred to. 70 is a pressure bar, suitably pivoted on the frame of the machine at 72; a weight 71, carried by an arm 71^a, is revolubly mounted on the pressure bar 70 at the pivoting point 72.

80

The free end of bar 70 is provided with a suitable shoe, as the convex member 73 which bears directly on the paper reel 67 to maintain the proper tension on the paper reel when the machine is in operation and prevent the reel from unwinding.

90

The action of such a brake is as follows:

As the reel is unwound, the pull exerted by the paper is gradually diminished as the radial distance diminishes between the tangential line of the paper and the center of the reel.

100

The ordinary brake bears on the reel in such a manner that the pressure on the reel increases as the brake descends because the vertical pull of gravity on the end of the brake bar is exerted at an increasingly greater horizontal distance from the fulcrum 72. But with my improved brake bar, as the weight 71 is raised, being also subjected to the same increasing pull of gravity, it thus counterbalances the increased pull on the brake shoe 73. Furthermore, by its revolubility around the fulcrum 72, an adjustment is provided that is very sensitive, and has range sufficiently wide for working any condition of paper.

110

For the purpose of taking up slack in the paper, my invention includes a tension means mounted on and co-acting with the braking means. This means may vary in construction within wide limits without departing from my invention.

120

I illustrate one form of tension means comprised in my invention consisting of a short lever 74, pivoted at 74^a to the bar 70 and having a convex portion which bears on the paper and follows the sag of the paper to whatever position it may take, as indicated by the numerals 68 and 75. When

130

the tension increases, this lever 74 takes up the slack of the paper. Even when the machine is started up with the paper very slack, the lever 74 provides a tension on the paper and allows the starting of the reel without a jerk. It thus avoids the breaking of the paper either on starting the machine or while running.

In machines of the character described, 10 it is necessary to drive the feeder as a whole at different speeds in order to deliver different quantities of tobacco on to the conveyer belt 13 according to the size of cigarette that is to be produced. This is generally accomplished by using a speed 15 changing device usually consisting of oppositely disposed cones with an intermediate driving belt whereby the speed of the feeder can be varied with reference to the 20 speed of the main shaft.

But in practice I have found that the use 25 of such cones does not produce a feed of sufficient regularity, particularly when making cigarettes of small diameters where the greatest possible regularity of feed is required. The inherent difficulty in a cone 30 and belt speed changing device lies in the fact that such a belt cannot pull its load on the center line, especially in a machine where the length of the belt is naturally restricted. As a result the pull is transmitted from opposite edges of such a belt. Again, as the 35 pull is comparatively heavy such belts have a tendency to stretch along the edges and they soon become wavy, so that the line of pull runs from one side to the other without possibility of being kept constantly in any one line. I have found that this results in an appreciable irregularity of feed regardless of all other causes.

Finding further that it is desirable, once 45 the feeder is set for a certain size of cigarette that it be driven at constant speed, it follows that positive means should be employed to transmit power to the feeder from the main shaft, so as to eliminate the above 50 variations and irregularities.

Still, provision must be made for changing 55 this speed when it is desired to make cigarettes of different cross sections. Means for accomplishing this result may vary within wide limits without departing from my invention, as for instance by using sprockets and chains of different sizes, or gear boxes 60 of various kinds or similar changeable means. By constructing a cigarette machine embodying the various features of my invention as herein described, I have found that the various difficulties above noted were avoided, and the resultant feed was all that 65 could be desired.

I will now describe the automatic feeder and its associated parts as more clearly disclosed in Figs. 3-4 and 5.

65 In Fig. 3, I illustrate a simple changeable

means of direct and positive transmission of power from the main shaft, to the automatic feeder of a machine of the kind described.

On main shaft 3 is mounted gear 23 which meshes with gear 24. The gears 24 and 25 70 are keyed together and mounted to revolve on the stud 49 carried by arm 50 which is pivoted on the shaft 3, see Figs. 3 and 9, the upper end of said arm being adapted to swing in the elongated arcuate slot 51, in 75 the housing 51^a to allow a change of the gear 25 of different sizes, to change the speed of the feeder to regulate the amount of tobacco fed on belt 13, according to the size of the cigarettes to be made. Stud 49 is held 80 in place by nut 52.

Gear 25 drives gear 26 which meshes with gear 27, carrying a bevel gear 28, the bevel gear 28 being more clearly shown in Fig. 2.

The bevel gear 28 drives the bevel gear 29, 85 which through shaft 29^a drives the worm 30 and the bevel gear 31. Bevel gear 31 drives bevel gear 31^a, which is secured to gear 31^b which in turn drives gear 20^a, which is secured to and drives the shaft of stripper roll 90 20, see Fig. 3, which may be of any of the usual kinds. The worm 30 meshes in worm wheel 32 which is secured to the shaft 32^a of the feeding roll 21 which it revolves. At the opposite end of the shaft 32^a of the roll 95 21 is secured a gear 33, see Fig. 5, which meshes with a pinion 34 on a stud secured to a quadrant 34^a in driving engagement with a gear 35 secured to the shaft 22^a of the dressing roll 22. In Fig. 5 the quadrant 34^a 100 is pivoted to swing on shaft 32^a and is secured to frame A by means of screws passing through slotted openings in the quadrant to provide an adjustment to pinion 34 to different sizes of gear 35 to obtain different 105 speeds to dressing roll 22.

To secure a regular and uniform feed in machines of the class described, it is necessary, as I have found, to fill up the spaces between the pins on the feed roll as evenly 110 as possible. To insure such filling, tampers of various kinds can be used without departing from my invention.

I illustrate one method of tamping, showing a connecting rod 37 secured to a crank 115 pin 36 attached to the gear wheel 26, the other end of the connecting rod being adjustable and pivotally connected as with an arcuate slot to the lever 38 which oscillates the shaft 39, Fig. 4, thereby oscillating the 120 tampers 40 which are secured to said shaft 39, said tampers tamping the tobacco into the teeth of the feeding roll 21, any excess of tobacco being dressed off by the dressing roll 22 as the feed roll carries the tobacco to 125 the stripper roll 20.

In practice it is very difficult to present tobacco to the feed roll without the tobacco developing a tendency to pack or mass against the face of the roll. The pins in the 130

roll as they work against the face of such a mass, tend to take out only the fibers that lie in the path of the pins. If the fibers lying between the paths of the pins are not disturbed, they tend to gradually pack up against the smooth portions of the feed roll between the pins. In time, as the pins reach comparatively few of the fibers, the feed becomes irregular. The operator must then 5 agitate the mass of tobacco in the hopper and so loosen the bridged or packed portions of such mass. The irregularity of feed produced by such packing results in loss of 10 production of salable cigarettes as well as a loss of material and time.

Such tendency to packing or massing varies with different tobaccos, so that it is necessary to be able to control the presentation of the tobacco to the feed roll.

20 After much experiment I have found that by intermittently presenting tobacco to the feed roll 21, as by moving the feed belt 41 at intervals, this packing or massing is avoided. Means for intermittently operating the belt may vary within wide limits 25 without departing from my invention. As an illustration of my invention, I show a feed belt 41 mounted in the hopper A on rollers 41^a, a ratchet 42 is fastened to the 30 roller shaft 42^a. The pawl 43 is mounted on a lever 44, which is attached to connecting rod 45, taking motion from the gear 33.

By experiment, I have further proved that 35 in machines of the class described, the feed can be better regulated if the presentation of the tobacco to the feed roller is controllable according to the condition of different tobaccos.

Means of control for presenting means 40 may vary widely without departing from my invention. One simple and effective means is illustrated in Fig. 5 in connection with the intermittent feed belt. A yoke 48 is secured to the gear 33, and is provided with a slot 47 in which the connecting rod 45 is pivotally and adjustably mounted to adjust the 45 stroke of the pawl 43 and ratchet 42 to vary the intermittent forward motion of the belt 41, which carries the tobacco forward to the 50 feed roll 21.

The tobacco from the hopper A is stripped from the feed roll 21 by the stripper roll 20 into the channel 56 on to belt 13 which carries it under the pressure wheel 55, which 55 compresses the tobacco on the belt 13, after which it is gathered by the disks 10 and 11 which form the filler for the filling of the cigarettes.

After the filler is formed, it meets the 60 strip of wrapping paper at the mouth of the wrapping tube T, which wraps the paper around the filler and in which the edges of the paper are joined together to form a continuous cigarette rod, said rod being afterward cut to lengths to form the cigarettes.

The wrapping tube T may be of any type usually found on machines of this character without departing from my invention and the joining or seaming device and the cutting device may likewise be of any usual type 70 so that none of these parts require detailed description in this specification.

Claims:

1. In a cigarette machine, the combination of a feeder, delivering tobacco in loose form, a 75 feed belt receiving tobacco from said feeder, a disk and its coacting member acting upon the body of tobacco to form it laterally as it is presented by said feed belt, a presser-wheel coacting with the belt to reduce the 80 body of tobacco perpendicularly to said lateral forming, immediately before it reaches said disk, means for positively driving said presser-wheel, and means for holding said presser-wheel in pressing position, adapted 85 to yield over an abnormal or non-yielding body passing beneath the presser-wheel.

2. In a cigarette machine, the combination of a feeder, delivering tobacco in loose form, a feed belt receiving tobacco from said 90 feeder, a disk and its coacting member acting upon the body of tobacco to form it laterally as it is presented by said feed belt, a presser-wheel coacting with the belt to reduce the body of tobacco perpendicularly to 95 said lateral forming, immediately before it reaches said disk, means for positively driving said presser-wheel, and means for holding said presser-wheel in pressing position, adapted to yield over an abnormal or non- 100 yielding body passing beneath the presser-wheel; said last-named means comprising a spring-pressed lever in which the wheel has bearing.

3. In a cigarette machine, the combination 105 of a feeder, delivering tobacco in loose form, a feed belt receiving tobacco from said feeder, a disk and its coacting member acting upon the body of tobacco to form it laterally as it is presented by said feed belt, a 110 presser-wheel coacting with the belt to reduce the body of tobacco perpendicularly to said lateral forming, immediately before it reaches said disk, means for positively driving said presser-wheel, and means for holding 115 said presser-wheel in pressing position, adapted to yield over an abnormal or non-yielding body passing beneath the presser-wheel; said last-named means comprising a spring-pressed lever in which the wheel has 120 bearing, and a stop adjustable at will for limiting the approach of the presser-wheel toward the feed belt.

4. In a cigarette machine, the combination 125 of a feeder, delivering tobacco in loose form, a feed belt receiving tobacco from said feeder, a disk and its coacting member acting upon the body of tobacco to form it laterally as it is presented by said feed belt, a presser-wheel coacting with the belt to re- 130

- duce the body of tobacco perpendicularly to said lateral forming, immediately before it reaches said disk, means for positively driving said presser-wheel, and means for holding said presser-wheel in pressing position, adapted to yield over an abnormal or non-yielding body passing beneath the presser-wheel; said last-named means comprising a rotary member in which said presser-wheel 5 has eccentric bearing, a spring imparting rotation to said rotary member, and a screw adjustable at will to limit such rotation.
5. In a cigarette machine, the combination of a feeder, delivering tobacco in loose form, 10 a feed belt receiving tobacco from said feeder, a disk and its coacting member acting upon the body of tobacco to form it laterally as it is presented by said feed belt, a presser-wheel coacting with the belt to reduce the body of tobacco perpendicularly to 15 said lateral forming, immediately before it reaches said disk, means for positively driving said presser-wheel, and means for holding said presser-wheel in pressing position, adapted to yield over an abnormal or non-yielding body passing beneath the presser-wheel; said feed belt having a flat, tobacco-supporting surface, and said presser-wheel having a plain cylindrical surface through 20 which it coacts with said belt.
6. In a cigarette machine, the combination of a tobacco feeder, a feed belt forwarding tobacco delivered therefrom, a filler-forming disk and its coacting member acting 25 horizontally upon the tobacco presented by the feed belt, a shaft for said disk, a lever-bearing for said shaft, a spring actuating said lever-bearing tending to move the bearing in a direction to impart pressure to said disk, and means through which to limit the movement of said bearing under the action 30 of the spring.
7. In a cigarette machine, the combination with wrapping means, and means conveying 35 tobacco to said wrapping means, of a positively driven pressure wheel for vertically reducing the body of tobacco on the conveying means, and a filler-forming disk and its coacting member laterally compressing and 40 forming the tobacco on said conveying means immediately after it is vertically reduced by the presser-wheel, shafts for said wheel and said disk, an eccentric bearing for each of said shafts, a spring actuated lever 45 for each of the bearings tending to turn the bearings in the direction to impart pressure respectively to the wheel and the disk, and arresting means for each bearing limiting its turning under the action of its spring.
- 50 8. In a cigarette machine, the combination of a revolving feed roll adapted to pick tobacco from a supply presented to it, a feed belt adapted to present a supply of tobacco to said feed roll, and means to move said 55 feed roll intermittently, toward said feed roll, 60 while said feed roll is revolving.
9. In a cigarette machine, the combination with a feed hopper, a feed roll, and a feed belt, of means to move said belt intermittently in one direction while said feed roll is 65 revolving and means to vary the movement of said belt.
10. In a cigarette machine, the combination with a feed hopper, a feed roll, means for tamping tobacco on said feed roll, and a feed belt, of means to move said belt intermittently.
11. In a cigarette machine, the combination with a feed hopper, a feed roll, tamping means co-acting with said feed roll and a feed belt, of a pawl and ratchet mechanism for intermittently moving said feed belt.
12. In a cigarette machine the combination with a feed hopper, a feed roll, tamping means co-acting with said feed roll and a feed belt, of a pawl and ratchet mechanism for intermittently moving said feed belt and means for varying the movement of said belt.
13. In a cigarette machine, the combination with a feed hopper, a feed roll and a feed belt, of adjustable means for intermittently moving said belt and means for tamping tobacco on the feed roll.
14. In a cigarette machine, the combination with a main shaft, a feed hopper, a feed roll, means for tamping tobacco on said feed roll, a dressing roll, and a stripper roll, of gearing means transmitting motion from said main shaft to said feed roll, dressing roll and stripper roll, an intermittently operating feed belt, and means for varying the movement of said belt.
15. In a cigarette machine, the combination with a main shaft, a feed hopper, a feed roll, a dressing roll and a stripper roll, of gearing means for transmitting motion from the main shaft to said feed roll, a dressing roll and a stripping roll, an intermittently operating feed belt and means for varying the travel of said belt.
16. In a cigarette machine, the combination with a main shaft, a feed hopper, a feed roll, means for tamping tobacco on said feed roll, a dressing roll and a stripper roll, of gearing means transmitting motion from said main shaft to said feed roll, dressing roll and stripper roll.
17. In a cigarette machine, the combination with the main shaft, a feed hopper, a feed roll, a dressing roll and a stripper roll, of a feed belt operating intermittently in one direction and in a horizontal plane while said feed roll is revolving, means transmitting motion from said main shaft to said feed roll, dressing roll and stripper roll and to said intermittently operating feed belt.

18. In a cigarette machine, the combination with wrapping means, pulleys and a belt mounted on said pulleys for conveying tobacco to said wrapping means, of rollers 5 adjustably mounted between said pulleys and contacting with the rims thereof and means controlling the position of said rollers.
19. In a cigarette machine, the combination with wrapping means, pulleys and a belt mounted on said pulleys for conveying tobacco to said wrapping means, of adjustable means mounted between and contacting with said pulleys to control the tension of 15 said belt.
20. In a cigarette machine, the combination with wrapping means, pulleys and a belt mounted on said pulleys for conveying tobacco to said wrapping means, of a laterally movable axis for one pulley, an adjustably mounted roller contacting with said pulley and means controlling the position of said roller to regulate the tension of said belt.
- 25 21. In a cigarette machine the combination with wrapping means, pulleys and a belt mounted on said pulleys for conveying tobacco to said wrapping means, of slidably mounted adjustable means for spreading the 30 pulleys apart by transmitting pressure from one pulley to the other.
22. In a cigarette machine the combination with positively driven filler-forming disks, of a traveling belt for conveying tobacco to 35 said disks, a wheel operating above the belt in advance of said disks, gearing for continuously revolving said wheel and a spring actuated lever carrying said wheel.
23. In a cigarette machine the combination with positively driven filler-forming disks, of a traveling belt for conveying tobacco to said disks, a gear driven wheel operating above said belt in advance of said disks, means including a lever for holding 45 said wheel yieldingly depressed toward said belt and means for manually adjusting the normal height of said wheel above said belt.
24. In a cigarette machine the combination with a traveling belt for conveying tobacco, of gear driven disks operating laterally upon the tobacco above said belt for forming a cigarette filler, means including a lever mounting for holding one of said disks yieldingly in operative position and means 50 for limiting the approach of the edges of said disks.
25. In a cigarette machine the combination with a traveling belt for conveying tobacco, of positively driven disks operating laterally upon the tobacco above said belt 60 for forming a cigarette filler, a spring actuated lever forming an eccentric bearing for one of said disks and means for manually adjusting the spring pressure.
26. In a cigarette machine the combination with a traveling belt for conveying tobacco, of gear driven disks operating above said belt for forming a cigarette filler, a spring actuated lever carrying one of said 70 disks, means for manually adjusting the spring pressure, and the distance between the edges of said disks.
27. In a cigarette machine, the combination with wrapping means, of means conveying tobacco to said wrapping means, said 75 conveying means comprising a traveling belt, a positively driven pressure wheel, and means for holding said wheel yieldingly depressed toward said belt.
28. In a cigarette machine, the combination with a filler forming disk, and a shaft for said disk, of an eccentric bearing for said shaft, a spring actuated lever on said bearing tending to turn the bearing in a direction to impart pressure to said disk. 80
29. In a cigarette machine, the combination with a filler forming disk, and a shaft for said disk, of an eccentric bearing for said shaft, a spring actuated lever on said bearing tending to turn the bearing in a 90 direction to impart pressure to said disk, and means for manually adjusting the spring pressure.
30. In a cigarette machine, the combination with wrapping means, and means conveying tobacco to said wrapping means, of a positively driven pressure wheel and a 95 filler forming disk coacting with said conveying means, a shaft for each of said wheels and said disk, an eccentric bearing 100 for said shaft, a spring actuated lever for the bearing tending to turn the bearing in a direction to impart pressure respectively to said wheel and said disk.

The foregoing specification signed at Cincinnati, Ohio, this thirteenth day of December, 1913.

ALBERT DU BRUL.

In presence of two witnesses:

HARRY WHYRICK,
F. CHUDOBA.
